CRADLE GYM

Albert Stubbmann, Franklin Lakes, N.J., assignor to
Kohner Bros., Inc., East Paterson, N.J., a corporation
of New York

Filed Jan. 12, 1970, Ser. No. 20,878

Term of patent 14 years

Int. Cl. D21—02

U.S. Cl. D34—15

FIG. 1

FIG. 2

FIG. 3

I

FIG. 5

FIG. 4

FIG. 1 is a front elevational view of a cradle gym showing my new design;

FIG. 2 is a side elevational view thereof;

FIG. 3 is a top view of the cradle gym;

FIG. 4 is a bottom view of the cradle gym, and

FIG. 5 is a sectional view through the frame, the same being taken substantially along the line 5—5 of FIG. 1.

The opposite side is the same as the side illustrated, and the back is the same as the front.

I claim:

The ornamental design for a cradle gym, substantially as shown and described.
